UNITED STATES PATENT OFFICE.

JOHN BERRY, OF LLANDUDNO, WALES.

APPARATUS FOR CONTROLLING INTERNAL-COMBUSTION ENGINES.

1,235,544.

Specification of Letters Patent.

Patented Aug. 7, 1917.

Application filed October 22, 1915. Serial No. 57,833.

To all whom it may concern:

Be it known that I, JOHN BERRY, a subject of the King of Great Britain, and residing in Llandudno, in the county of Carnarvon, North Wales, Great Britain, have invented certain new and useful Improvements in Apparatus for Controlling Internal-Combustion Engines, of which the following is a specification.

10 This invention relates to improvements in apparatus for controlling the carburetors of internal combustion engines especially applicable to automobile engines, and the object is to facilitate starting, to economize fuel, and to provide for increased power when required. The invention is applicable generally to carburetors, but is especially applicable to the "Holley" carburetor as fitted to the well known "Ford" cars, in connection with which carburetor the invention will, by way of example, be described.

The invention is illustrated in the accompanying drawings, in which Figure 1 is a plan view, Fig. 2 a corresponding elevation, 25 Fig. 3 a view, in section on the line III, III, of Fig. 2, showing the guide pulley and lever. Fig. 4 a view, in section on the line IV, IV, of Fig. 1, showing the needle valve spindle and pulleys, and Fig. 5 a view, 30 partly in section on the line V, V, of Fig. 1, showing the throttle valve with its spindle and operating lever.

Throughout the drawings the same parts are indicated by the same reference characters, and in the case of sections the direction in which they are viewed is indicated by the small arrows placed adjacent to the letters denoting the plane of section.

40 A is the carburetor which, as stated, is of the well known "Holley" type. B is the needle valve spindle of the carburetor. The spindle is coned as shown at b¹, Fig. 4, so as to form a valve to control the fuel supply opening, and its position axially determines 45 the extent of opening of the fuel supply port a¹ to which fuel is fed through the lateral ports a² from the tank a³ in which the level is maintained uniform by any suitable and well known device. The portion b² of the spindle B is screw-threaded, 50 and fits a correspondingly screw-threaded part a⁴ of the cover of the carburetor, so that rotation of the spindle imparts axial movement to it. The outer end of the 55 spindle is provided with a hand adjusting

disk b³ which is secured non-rotationally to the spindle B.

Between the disk b³ and the cover of the carburetor a double pulley C is provided; the upper portion c¹ is of larger diameter 60 than the lower portion c². This pulley is adjustably fixed on the spindle B by means of a set screw c³. A flexible chain or band c⁴ passes around the portion c¹ of the pulley C and is anchored thereto by any suitable anchoring attachment c⁵; one end of the chain c⁴ is attached to one end, d¹, of a spring D, the other end d² of which is connected to a bracket d³ the position of which can be adjusted relatively to the fixed part 65 d⁴, holes d⁵ being provided for this purpose. The spring D is so arranged in relation to the pulley and to the "hand" of the screw-threaded part b², that, when stretched, it tends to rotate the spindle B so as to open 70 the fuel supply port a¹.

The other end of the chain c⁴ is connected to the end e¹ of a spring E the other end e² of which is connected by a flexible wire or chain e³ to a lever f¹ on the ignition 80 control rod F of the car, the chain or wire e³ passing around the guide pulley e⁴ carried on the two-armed bracket e⁵ which in turn is secured to any suitable part of the engine—say the holding brackets e⁶. 85

Angular motion imparted to the rod by the driver controls the ignition by advancing or retarding the spark in any suitable and well known manner.

In the arrangement shown in the drawings, it is assumed that in order to advance the spark, the rod F is rotated in the direction shown by the arrow f² Fig. 1.

The spring E is more powerful than the spring D, and it will be seen therefore that 95 when the ignition control rod F is rotated in the direction indicated by the arrow f², the lever f¹ draws the wire e³ over the guide pulley and stretches the spring E, whereupon the spring D yields, and the pulley C 100 and spindle B turn in the direction indicated by the arrow b⁴ to close the port a¹; the tension of the spring and the length of the lever f¹ are usually so arranged that when the ignition rod F has been moved to 105 the limit giving the maximum advance spark, the rotation imparted to the spindle B causes it to close or almost close the fuel supply port a¹. When the ignition control rod F is moved in the opposite direction to 110

the arrow f^2 , the spring E relaxes, whereupon the tension of the spring D rotates the pulley C and spindle B so as to open the fuel supply port a^1 .

- 5 G is the throttle valve which controls the supply of carbureted gas to the engine, and on the spindle g^1 of the throttle a lever g^2 is fixed; this lever is connected by a rod g^3 to a lever h^1 on the throttle control rod H, 10 the joint at the end g^4 of the rod g^3 being a universal or ball joint, and the connection between the other end of the rod g^3 and the lever g^2 having sufficient play to accommodate the slight lateral movement of the 15 rod. When the throttle control rod H is turned in the direction indicated by the arrow h^2 , Fig. 1, the throttle is opened.

An extension g^5 is fixed by adjustable means to the throttle lever g^2 ; in the arrangement illustrated, g^5 is fixed relatively to g^2 by the screw g^6 ; this permits angular adjustment of the extension g^5 relatively to g^2 . The movement of g^2 is limited in the one direction by the adjustable screw g^7 25 and the stop g^8 . A chain c^6 coiled around the smaller diameter c^2 of the pulley C and anchored thereto is connected to the end of the extension lever g^5 .

The fixed relationship between the extension lever g^5 and the throttle lever g^2 , and the length of the chain c^6 , are so arranged that when the throttle valve, as it opens, reaches a predetermined point, the chain c^6 is pulled taut, whereupon further movement of the throttle and its lever g^2 imparts angular movement to the pulley C, rotating the spindle B in opposition to the spring E and opening the fuel supply port a^1 .

The control rods F and H are usually 40 arranged alongside and parallel with the steering post K of the car, and each is provided with a lever under the control of the driver and moving over a notched quadrant.

The carburetor is fitted with a by-pass 45 and the usual accessory parts, but as these are not material to the present invention, they are not described herein.

The action of the apparatus is as follows:—

50 The needle valve spindle B is set so as to give the correct fuel supply for normal running or for any predetermined speed, and the pulley C is then adjusted on this spindle so that the springs D and E are approximately in equal tension when the ignition control rod F is in mid position. The pulley C is then fixed in this position relatively to the spindle B by the set screw c^9 .

In starting the engine, the ignition 60 control rod is turned in a direction opposite to that indicated by the arrow f^2 so as to retard the spark, whereupon the tension in the spring E is reduced, and the tension of the spring D rotates the spindle C so as to increase the effective opening of the

port a^1 whereby the rate of fuel supply is increased, and a rich carbureted mixture provided.

After starting, the spark is advanced by 70 rotating the ignition control rod in the direction indicated by the arrow f^2 , whereupon the opening of the fuel supply port is diminished and the rate of the fuel supply correspondingly decreased.

When extra power is required, the throttle valve is opened beyond the predetermined point at which the chain c^6 is pulled taut by the lever g^5 , whereupon movement of the throttle valve beyond this point to increase the throttle opening is effective in so imparting, through the lever g^5 and chain c^6 , angular movement to the spindle B in such direction as to increase the opening of the fuel supply port a^1 , to increase the rate of fuel supply, the spring E being stretched 85 and the spring D contracted; as the radius of the pulley c^2 is small as compared with that of c^1 , a small movement of the lever g^2 imparts comparatively large angular movement to the valve spindle.

90 For ordinary running the fuel supply valve spindle B is regulated by the movement of the ignition control rod only; when, however, extra power is required and the throttle control means are operated to obtain it, the spindle B is operated thereby as described so as to give the required increased supply; the independent operation of the spindle B by the throttle control means is permitted by virtue of the elastic connection between the spindle B and the ignition control means. The setting between the spindle B and the ignition control means is usually such that when the latter is in a position which gives extreme 95 advance sparking, the spindle B cuts off or almost cuts off the fuel supply.

100 The invention can, of course, be applied to carburetors other than of the "Holley" type, the details of construction being modified accordingly.

Having now fully described my invention, I declare that what I claim and desire to secure by Letters Patent is:—

115 1. In a carburetor, in combination; a fuel supply valve; elastic means tending normally to open the fuel supply valve; a movable part under the control of the driver; elastic means connecting the said valve with the said movable part and adapted when the said part is moved in the one direction, to close the fuel supply valve; a throttle valve; means connecting the throttle valve to the said fuel supply valve and adapted when the throttle valve opens beyond a predetermined limit, to 120 open the fuel supply valve; substantially as described.

125 2. In a carburetor, in combination; a fuel supply valve; elastic means tending normally to open the fuel supply valve; means 130

for controlling the engine ignition; elastic means connecting the said valve with the said ignition controlling means and adapted, as the spark is advanced, to close the fuel supply valve; a throttle valve; means for operating the throttle valve; means connecting the throttle valve to the said fuel supply valve and adapted when the throttle valve opens beyond a predetermined limit, to open 10 the fuel supply valve; substantially as described.

3. In a carbureter, in combination; a fuel supply valve adapted when rotated to control the fuel supply; a pulley on the spindle 15 of said fuel supply valve; a spring one end of which is fixed to an adjustable part and the other end of which is connected to one end of a flexible member anchored to the pulley; a moving part adapted to control the 20 engine ignition; elastic means interposed between the other end of the said flexible member and the said moving part; a throttle valve; a lever connected thereto; a second pulley on the fuel supply valve spindle; a 25 flexible member anchored to the said second pulley and the free end of which is con-

nected to the throttle valve lever; substantially as described.

4. In a carbureter, in combination; a fuel supply valve adapted when rotated to control the fuel supply; a double grooved pulley 30 adjustably secured to the spindle of the said valve; a spring one end of which is fixed to an adjustable part and the other end of which is connected to one end of a flexible member 35 anchored to one of the grooves of the pulley; a moving part adapted to control the engine ignition; elastic means interposed between the other end of the said flexible member and the said moving part; a 40 throttle valve; a lever connected thereto; a second lever adjustably mounted thereon; a flexible member anchored to the second groove of the said pulley and the free end of which is connected to the said second 45 lever; substantially as described.

In testimony whereof, I affix my signature in presence of two witnesses.

JNO. BERRY.
